United States Patent [19]

Ingle

[11] Patent Number: Des. 321,241

[45] Date of Patent: ** Oct. 29, 1991

[54] COMBINED PRESSURE AND THERMAL SAFETY VALVE

[75] Inventor: Gary D. Ingle, Mound, Minn.

[73] Assignee: General Pump/U.S., Inc., Eagan, Minn.

[**] Term: 14 Years

[21] Appl. No.: 875,651

[22] Filed: Jun. 16, 1988

[52] U.S. Cl. D23/235

[58] Field of Search D23/233, 235, 247, 244-249, D23/269; 137/72, 74, 454.4, 454.2

[57]

CLAIM

The ornamental design for a combined pressure and thermal safety valve, as shown and described.

DESCRIPTION

FIG. 1 is a perspective view taken from the front and side of a combined pressure and thermal safety valve showing my new design;

FIG. 2 is a side elevational view thereof, the opposite side being a mirror image of the side shown;

FIG. 3 is a side elevational view taken 90° to the side shown in FIG. 2, the opposite side being a mirror image of the side shown;

FIG. 4 is a front elevational view thereof; and

FIG. 5 is a rear elevational view thereof.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 321,241
DATED : October 29, 1991
INVENTOR(S) : Gary D. Ingle

It is certified that error appears in the above-identified patent and that said Letters Patent is hereby corrected as shown below:

On the title page, item [22] Filed:
please delete the filing date of "Jun. 16, 1988" and substitute
therefore--June 16, 1986--.

Signed and Sealed this
Second Day of March, 1993

Attest:

STEPHEN G. KUNIN

Attesting Officer

Acting Commissioner of Patents and Trademarks
